UNITED STATES PATENT OFFICE

2,025,637

LUBRICATOR

William S. Boehm, St. Louis, Mo., assignor to Lincoln Engineering Company, St. Louis, Mo., a corporation of Missouri

Application August 11, 1934, Serial No. 739,445

10 Claims. (Cl. 308—84)

This invention relates to lubricators, and with regard to certain more specific features, to lubricators for journal boxes and the like.

Among the several objects of the invention may be noted the provision of an automatic, journal-box, lubricator pump which is operable by the side sway induced by movement of the vehicle on which the device is located; the provision of a pump of the class described which shall have an advantageous arrangement of parts adapted to be readily disassembled or to have replacements made while on the journal box; and the provision of a pump of the class described which shall have an improved and more dependable action. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a plan view of the pump;

Fig. 2 is a longitudinal section thereof; and,

Fig. 3 is a vertical section taken on line 3—3 of Fig. 1 showing an applicator.

Similar reference characters indicate corresponding parts throughout the several views of the drawing.

The general structure to which the structure of the present invention applies is shown in copending United States patent application of Frank S. Barks, Serial No. 738,954, filed August 8, 1934, for Lubricator, which is an improvement upon apparatus shown in United States Patent 1,948,297. As is shown in said application and patent, journals of locomotives and car wheels and the like may be provided with sumps which are fastened to the journal boxes and which carry a supply of lubricant. Pumps are provided in the sumps, the same having means whereby relative motion between the journal box and the journal effects operation of the pump to flush oil upon the journal.

However, it has not been disclosed heretofore how to construct a pump along the advantageous lines herein laid down. Prior pumps have been difficult to apply and remove for purposes of repair or replacement. The present pump may be quickly disassembled and reassembled for such purposes.

Referring now more particularly to Fig. 1 of

the drawing, there is shown at numeral 59 a cylinder having a head 61 which is welded at 63 to the sump 27. From the right-hand end of the cylinder 59 is introduced a reciprocating sleeve 65 having a pressed-in head 67 and a groove 69 with which cooperates an outwardly pressing spring ring 71, the latter limiting the movement of the sleeve.

The head 67 contacts with the hub of the locomotive wheel and responds by reciprocation in the cylinder 59 to lateral movement of the sump 27 with respect to the wheel. There is always such lateral movement between the sump and the wheel because of the side sway allowed between the journal box (to which is attached the sump) and the wheels. For more particulars in respect to the relationship between journal box, sump and wheels, see the references to the copending application and the patent above cited.

The interior of the head 67 contacts with, but is not joined to, a plunger stem 75 which at its inner end is formed as a plunger 77. The stem 75 carries a fixed head 73. A spring 79 normally reacts on head 73 to cause the plunger 77 to follow the motion of the head 67. The stem 75 is guided in a bushing 81 located in the end of a second cylinder 83 which carries said plunger 77. The member 77, 67, and 65 form what may be referred to as a plunger assembly within bushing 59.

The cylinder 83 has a slip fit with respect to the cylinder or bushing 59 and is provided with a dowel pin 85 which cooperates with a groove 87 in the cylinder 59 to effect a predetermined angular relationship between said cylinders 59 and 83.

The cylinder 83 carries an inlet check valve 89 and an outlet check valve 91, whereby reciprocation of the plunger 77 effects in drawing of the lubricant through the valve 89 and expulsion of the same through the valve 91. The valves are simple in construction consisting simply in a cylinder 11 held in a bore by a plug 1. The cylinder 11 is counterbored at each end as at 3 to accommodate the valves 89 which are simply balls. The plug is milled as at 5 to provide proper communications to the pump and outlet and the bores 3 and 5 communicate centrally by a bore 7. Opposite the counterbore 3 is an inlet bore 9 providing ingress to the valve. 50

From the valve 91, the lubricant is forced through a hollow stem 93 which is threaded to the cylinder 83, the same having a clearing internal fit with respect to an exhaust manifold cap 95, the latter serving in cooperation with the 55

left-hand end of cylinder 59 to support a strainer 97 for straining the oil which proceeds to the downwardly located check valve 89. The purpose of the predetermined angular relationship 5 determined by the dowel pin 85 and recess 81 is to maintain the inlet check valve 89 directed downwardly to as low a point as possible in the well of oil.

The hollow outlet 93 carries a shoulder 99 which cooperates with the manifold cap 95 to close the left end thereof. The closure 99 is provided with spanner wrench sockets 101 and a seat for a spring 103, the latter reacting against the opposite end of the sump 27 to force together the parts 83 and 59, thereby maintaining the assembly of the pump in the sump.

Demounting of the pump for making repairs is quite simple. All that is necessary is to pull back the spring 103 from the member 99. Thereafter parts 93, 95, 97, 83, 81, 75 and 79 may be withdrawn as a unit from the cylindric bushing 59. These may then be readily separated by unloosening member 99. The head 67 with the sleeve 65 may be drawn out in the opposite direction. Repairs thus may be quite readily effected.

The outlet manifold 95 carries an outlet pipe 105 which has a slip fit 107 in a recess of a lubricant well 109. The well 109 has a vertically slideable applicator 111 which is normally spring 30 pressed upwardly by means of spring 113, the same having a bearing on a stem 115 and being limited in its motion by a cross pin 117. The applicator includes a spread head 119 for contacting with the journal which is located above.

It will be seen that as the side sway takes place with the motion of the vehicle, the plunger which contacts the wheel, reciprocates to withdraw lubricant from the sump and force it through the manifold 95, pipe 105, well 109, and applicator 111 against any journal which may be located above the applicator.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing 50 shall be interpreted as illustrative and not in a limiting sense.

I claim:

1. In apparatus of the class described, a sump, a cylindric bushing within the sump and communicating with the exterior of the sump, a hollow cylindric reciprocating member in said bushing and adapted to be operated from the outside of the sump, a pump cylinder removably fitting said bushing, a plunger in said pump cylinder, and resilient means pressing said plunger in a direction to cooperate with the interior of said reciprocating member and partaking of the reciprocation thereof, inlet and outlet check valves associated with said pump cylinder and adapted to draw in and expel fluid under reciprocation of said plunger, an outlet member fastened to said pump cylinder, an outlet manifold held to the pump cylinder by the outlet member and resilient means pressing said outlet, said manifold and said pump cylinder into separable assembly with said first-named bushing.

2. In apparatus of the class described, a sump, a cylindric member within the sump, a second and hollow cylindric member reciprocable in said first-named member and adapted to be operated

from the outside of the sump, a third cylindric member interiorly of said first cylindric member, a plunger in said third cylindric member, resilient means pressing said plunger in a direction to cooperate with the interior of the second cylindric member to partake of the reciprocation of said second cylindric member, inlet and outlet check valves associated with said third cylindric member and adapted to draw in and expel fluid under reciprocation of said plunger, an outlet manifold, an outlet member fastened to said third cylindric member and adapted to hold said outlet manifold thereto, and resilient means pressing said outlet with said manifold and said third cylindric member into assembly with said first-named cylindric member.

3. In apparatus of the class described, a sump, a cylindric member within the sump, a second and hollow cylindric member reciprocable in said first-named member and adapted to be operated from the outside of the sump, a third cylindric member interiorly of said first cylindric member, a plunger in said third cylindric member, resilient means pressing said plunger in a direction to cooperate with the interior of the second cylindric member to partake of the reciprocation of said second cylindric member, inlet and outlet check valves associated with said third cylindric member and adapted to draw in and expel fluid under reciprocation of said plunger, an outlet manifold, an outlet member fastened to said third cylindric member and adapted to hold said outlet manifold thereto, and resilient means pressing said outlet with said manifold and said third cylindric member into assembly with said first-named cylindric member and a strainer held between said outlet manifold and said first-named cylindric member.

4. In apparatus of the class described, a sump, a cylindric member within the sump and communicating exteriorly of the sump, a second and hollow cylindric member reciprocable in said first-named member and adapted to be operated from the outside of the sump, a third cylindric member interiorly of said first cylindric member, a plunger in said third cylindric member, resilient means pressing said plunger in a direction to cooperate with the interior of the second cylindric member to partake of the reciprocation of said second cylindric member, inlet and outlet check valves associated with said third cylindric member and adapted to draw in and expel fluid under reciprocation of said plunger, an outlet manifold, an outlet member fastened to said third cylindric member and adapted to hold said outlet manifold thereto, and resilient means pressing said outlet with said manifold and said third cylindric member into assembly with said first-named cylindric member and a register means between said third cylindric member and said first-named cylindric member adapted to maintain a predetermined angular relationship between the two.

5. In apparatus of the class described, a sump, a bushing in the sump, said bushing communicating with the exterior of the sump, a reciprocating plunger cooperating interiorly with the bushing and reciprocable from the outside of the sump, a pump cylinder separably fitted within said bushing, a plunger in said cylinder, a resilient means normally forcing said plunger into engagement with said reciprocable member within the bushing, inlet and outlet check valves associated with said cylinder and adapted to draw in and expel fluid under reciprocation of said plunger, outlet means associated with the cylinder, and spring 55

means adapted to push the outlet means and said cylinder into separable cooperation with said bushing.

6. In apparatus of the class described, a sump,

- 5 a bushing in the sump, said bushing communicating with the exterior of the sump, a reciprocating plunger cooperating interiorly with the bushing and reciprocable from the outside of the sump, a pump cylinder separably fitted within said bushing, a plunger in said cylinder, a resilient means normally forcing said plunger into engagement with said reciprocable member within the bushing, inlet and outlet check valves associated with said cylinder and adapted to draw in and expel fluid under reciprocation of said plunger, outlet means associated with the cylinder, a spring means adapted to force the outlet means and said cylinder into cooperation with said bushing, and registered means located between the cylinder and said bushing for predeterminedly positioning said valves.

7. In apparatus of the class described, a sump, a bushing in the sump, said bushing communicating with the exterior of the sump, a reciprocating

- 25 member cooperating interiorly with the bushing and reciprocable from the outside of the sump, a pump cylinder separably fitted within said bushing, a plunger in said cylinder, a resilient means normally forcing said plunger into engagement with said reciprocating member within the bushing, inlet and outlet check valves associated with said cylinder and adapted to draw in and expel fluid under reciprocation of said plunger, outlet means associated with the cylinder, spring means adapted to force the outlet means and said cylinder into cooperation with said bushing, registered means located between the cylinder and said bushing for predeterminedly positioning said valve, an applicator and a pipe having a slip fit with said applicator and connected with said outlet means, the movement for effecting said slip fit and application of the cylinder to the bushing being the same.

8. In apparatus of the class described, a sump,

- 45 a bushing in the sump, a pump cylinder separably fitted within said bushing, inlet end outlet valves associated with said cylinder and adapted to draw in and expel fluid under reciprocation of said pump plunger within the pump cylinder, outlet means associated with the cylinder, an applicator, and a pipe having a slip fit with said applicator and connected with said outlet means, the movement for effecting said slip fit and application of the cylinder to the bushing being the same, and spring means holding said

cylinder to the bushing and the pipe to the applicator.

9. In apparatus of the class described, a sump, a bushing in said sump, said bushing communicating with the exterior of the sump, a plunger assembly guided within said bushing and adapted to be reciprocated from the outside of said sump, a cylinder having a slip fit with said bushing and with which a portion of said plunger assembly cooperates, resilient means forcing said plunger assembly outwardly, inlet and outlet valve means in said cylinder, whereby reciprocation of said plunger assembly effects pumping of fluid into and out of the cylinder, registry means between the cylinder and the bushing adapted to predeterminedly position the valve means, hollow outlet means screwed to the cylinder, means clamped between said hollow outlet means and the cylinder functioning as an outlet manifold, resilient means forcing the assembly of manifold, outlet means and cylinder into cooperation with said bushing, an applicator, and a pipe connecting said outlet manifold with said applicator, said pipe and said applicator having a slip fit, the movement for effecting said slip fit and applying said cylinder to the bushing being parallel.

10. In apparatus of the class described, a sump, a bushing in said sump, said bushing communicating with the exterior of the sump, a plunger assembly guided within said bushing and adapted to be reciprocated from the outside of said sump, a cylinder having a slip fit with said bushing and with which a portion of said plunger assembly cooperates, resilient means forcing said plunger assembly outwardly, inlet and outlet valve means in said cylinder, whereby reciprocation of said plunger assembly effects pumping of fluid into and out of the cylinder, registry means between the cylinder and the bushing adapted to predeterminedly position the valve means, hollow outlet means screwed to the cylinder, means clamped between said hollow outlet means and the cylinder functioning as an outlet manifold, resilient means forcing the assembly of manifold, outlet means and cylinder into cooperation with said bushing, an applicator, and a pipe connecting said outlet manifold with said applicator, said pipe and said applicator having a slip fit, the movement for effecting said slip fit and applying said cylinder to the bushing being parallel.
